UNITED STATES PATENT OFFICE.

FRANCIS W. CARPENTER, OF HARRISON, NEW YORK.

TOY HORSE.

SPECIFICATION forming part of Letters Patent No. 241,188, dated May 10, 1881.

Application filed March 28, 1881. (No model.)

To all whom it may concern:

Be it known that I, FRANCIS W. CARPENTER, of Harrison, in the county of Westchester and State of New York, have invented an Improvement in Toy Horses, of which the following is a specification.

Toy horses have been provided with wheels and cranks that are connected to the horses by rigid strips of metal, so that as the cranks are revolved by the wheels the horses are moved to imitate cantering. In this case the horses' feet are kept out of contact with the floor, so as to allow of the unimpeded movement of the crank.

In my present invention the pivoted toy horse is moved by a flexible connection to the bit or head, and the crank is of a sufficient length to lift the hind legs of the toy horse from the floor and then allow the rear portion of the horse to drop by its superior weight and the hind feet to rest on the floor until the flexible connection is again drawn upon sufficiently to pull down the head and raise the hind legs.

In the drawings, Figure 1 is a plan of two toy horses and the actuating-wheels. Fig. 2 is a side view of the same; and Fig. 3 is an elevation of a single toy horse upon wheels.

The tongue *n* and cross-bar *f* may be similar to those in my Patent No. 234,534, and there is a wire, *o*, forming a pivot for the horses *A* *B* to swing upon, but said pivot-wire is fastened at its middle to the tongue *n* and has the movable pins *v* *v*, one at each end, to hold the toy horses in place. The cords *a* *a* form the traces, and these are attached at the ends of the cross-bar *f* and provided with loops at the outer ends, that are slipped over the ends of the wire *o* after the horses are put in place and before the pins *v* are inserted through the holes in such wire *o*.

The wheels *c* are each made with teeth around the periphery, to insure the rotation when drawn over the floor, and the axle *e* for said wheels passes through the downward projection from the tongue *n*. These wheels are independent of each other, and each wheel has a crank-pin, *t*, and a flexible connection, *k*, to the front part of the horse, preferably to the head. I prefer to employ a short piece of sheet metal for the crank-pin *t* to pass through, and connect to the same a small strap of leather or other material passing to the mouth of the toy horse, so that the crank will pull down the head of the horse and swing it upon the pivot-wire *o*, raising the

hind part of the horse; and when the crank-pin 55 passes its lowest point the horse will swing the other way in consequence of the back end being heaviest, and the hind leg will rest upon the floor or other support, and thus a motion will be given to the two horses independently 60 in an amusing manner as the toy is drawn along.

Fig. 3 shows a single horse pivoted on a frame with four wheels, and there is a crank and flexible connection from one of the wheels 65 to the head of the horse, so as to give to the toy the movements before described.

The bits *p* for the horses are made of short wires passed through the metal at the mouth portion of the toy horse. There is a washer 70 near each end, secured by the ends of the wire being riveted, and the wire bit projects sufficiently for the flexible connection *k* to be passed over it.

I claim as my invention—

1. The combination, with a pivoted toy horse and wheel and crank, of a flexible connection from the crank to the front portion of the toy horse, substantially as set forth.

2. In a toy, the combination of a tongue, *n*, 80 pivot-wire *o*, toy horses *A* and *B*, wheels *c* *c*, cranks *t* *t*, and flexible connections from the cranks to the forward portion of each horse, substantially as set forth.

3. A toy horse pivoted so that one end is 85 heavier than the other, in combination with a wheel and crank-pin, and a flexible or yielding connection from the crank-pin to the lightest end of the toy horse, substantially as set forth.

4. The wheel *c*, with a toothed periphery and 90 a crank-pin, in combination with a pivoted toy horse, and a connection from the crank to the horse, as set forth.

5. In a toy, the flexible traces *a* *a*, attached at their back ends and having loops at their 95 front ends, in combination with the toy horses and the pivot-wire, over which the trace-loops are passed, as set forth.

6. In a toy horse, a bit formed of a wire passing through the toy at its mouth, and provided with washers secured by the riveted ends of the wire, as set forth.

Signed by me this 26th day of March, A. D. 1881.

FRANCIS W. CARPENTER.
